UNITED STATES PATENT OFFICE.

FRANK GERHART, FREDERICK FREY, AND CARL TESKE, OF SAN FRANCISCO,
CALIFORNIA.

DESIGN FOR A COMBINED STREET INDICATOR AND ADVERTISING PILLAR.

Application filed June 1, 1925. Serial No. 13,627. Term of patent 7 years.

To all whom it may concern:

Be it known that we, FRANK GERHART, FREDERICK FREY, and CARL TESKE, citizens of the United States, and a citizen of Germany, residing at San Francisco, in the county of San Francisco, State of California, have invented a new, original, and ornamental Design for Combined Street Indicator and Advertising Pillar, of which the following is a specification, reference being had to the accompanying drawing, forming part thereof.

The figure is a perspective view of a combined street indicator and advertising pillar, showing our new design.

We claim:

The ornamental design for a combined street indicator and advertising pillar, as shown.

FRANK GERHART,
FREDERICK FREY,
CARL TESKE.
